UNITED STATES PATENT OFFICE.

HENRY E. BRYANT, OF PROVIDENCE, RHODE ISLAND, ASSIGNOR TO TUBULAR WOVEN FABRIC COMPANY, OF PAWTUCKET, RHODE ISLAND, A CORPORATION OF RHODE ISLAND.

CIRCULAR LOOM.

Application filed November 18, 1921, Serial No. 516,096. Renewed August 20, 1924.

This invention relates to circular looms and its main objects are to enable a greater number of warp threads to be woven into a tubular fabric and to enable a larger supply 5 of filling yarn to be carried by the shuttle, in a loom of given size, than has heretofore been possible. Other objects subsidiary and contributory to those here named appear from the following detailed description of 10 a form of loom by which they are carried into effect.

These objects are accomplished by constructing the frame of the loom with a central tubular post and a circular head of substantially larger diameter than the post, by mounting the heddle mechanism around the post at a substantial distance below the head, and by so constructing the shuttle that the bobbin carried thereby is located close to the 20 post below the head and above the heddle mechanism.

The invention consists in a loom having these characteristics and other features, and equivalents thereof, hereinafter described 25 and claimed in connection with the detailed description of a specific machine embodying the invention.

In the drawings,—

Figure 1 is a side elevation of the specific 30 loom above referred to.

Figure 2 is a vertical central section.

Figure 3 is a plan view of the loom with part of the head broken away and two of the 35 shuttles shown in horizontal section on respectively lines *a—a* and *b—b* of Figure 1.

Figure 4 is a horizontal section taken approximately on line 4—4 of Figure 1 and showing the heddle motion in plan.

Figure 5 is a detail side elevation of the 40 yarn carrying part of the shuttle, showing the mode of mounting and releasing the filling yarn bobbin.

Figure 6 is an elevation showing in detail the spindle which carries the filling yarn.

Figure 7 is a plan view of the brace by 45 which the swinging end of such spindle is secured.

Figures 8 and 9 are detail views of the heddle mechanism.

Like reference characters indicate the same 50 parts wherever they occur in all the figures.

The loom here illustrated is adapted to weave seamless tubing of a large range of diameters with from one to four (or more) 55 filling yarns. Ordinarily at least two

shuttles will be used to give balance, and preferably four are used to obtain rapid production of the woven product. In Figure 2 two shuttles are shown and in Figure 3 four shuttles.

The frame consists of a hollow post 10 having on its upper end an enlarged head 11, and its bottom end being secured to a flange 12 which rests upon and is fastened to a base or pedestals 13 having legs 14 or equivalent devices for mounting upon a floor or other bed.

The head 11 is substantially circular in outline, and in or on its upper side is a circular guideway or track 15 for the shuttle. As 70 here shown, this track is a groove bounded by overhanging lips 16 and 17 formed to embrace and confine the shuttle base 18. Such shuttle base is shaped to conform with the guideway, both in cross section and in length, 75 as appears from Figures 2 and 3, and it has substantial length. I may note here that other specific constructions or forms may be given to the complementary shuttle base and guideway, provided they are so made that the shuttle is guided to travel in a substantially circular path and is suitably retained in the guideway.

For driving the shuttles there is provided a shaft 19 mounted in the post 10 and carrying a bevel gear wheel 20, in mesh with a series of bevel pinions 21, carried by radially arranged shafts 22, which turn in suitably arranged bearings in the head, and each of which carries also a shuttle driving pinion 23 adapted to mesh with rack teeth 24, provided on the under side of the shuttle base. These shafts and pinions are so spaced along the trackway, and the shuttle base 18 has such length, that at least one driving pinion 95 23 is always in mesh with the teeth on the shuttle base, whereby the shuttle is passed on from each pinion to the next without intermission. This condition may be also expressed by the statement that the length of the shuttle base in the direction of its travel is greater than the space between any two driving pinions. Preferably, however, the base is long enough to overlie nearly the whole of two of these spaces, being thereby 100 engaged most of the time with two pinions at once. As all the bevel pinions 21 are of the same diameter and pitch, and all the driving pinions 23 are also of the same diameter and pitch, the shuttle is driven 105 110

smoothly at a uniform rate of speed and comes into mesh accurately with each successive driving pinion.

The head is recessed or depressed within 5 the peripheral part where the guideway is formed, sufficiently to receive the pinions and give room for assembling them with the shafts 22.

The shuttle includes, besides the base 18, 10 a bar 25 which constitutes a frame or carrier, a filling yarn or bobbin holder, and a weft packer. The bar 25 extends across the base, to which it is fastened by any suitable means, and one end is directed toward the 15 weaving point at the center of the loom while in the other direction the bar extends over and around the rim of the head, and then downward, with an inclination in part toward the post. This bar may be considered 20 as an angularly formed frame which has a horizontal part 25^a overlying the base or slide 18 and a depending part 25^b below the head and beside the post of the frame. This depending part is provided near its lower 25 end with a supporting bracket 26 whereon a bobbin holding spindle 27 is mounted, and it is provided at a distance above this bracket with a second bracket or spindle retainer 28 by which the upper end of the spindle is 30 held and made steady. These brackets project from the bar member 25^b tangentially of the loom frame and preferably in the opposite direction to the travel of the shuttle.

A bobbin, or spool, or tube 29, on which is 35 wound a supply of filling yarn 30, is adapted to be slipped on and off from the spindle 27; and in order to permit mounting and dismounting of such a bobbin, etc., the spindle is pivoted to the lower bracket and detach- 40 ably connected with the upper bracket in such manner that it may be swung clear of the upper bracket. Preferably the arrangement of the spindle is such that this swinging movement takes place in a plane more or 45 less radial to the loom but not necessarily so. A pivot 31 supported in lugs on the bracket 26 holds the lower end of the spindle, while a locking pin 32 secures the upper end of the spindle detachably to the upper 50 bracket. This locking pin projects from the end of the spindle and is partly contained in a socket therein. It is acted upon by a spring 33 pressing against a head 34 and reacting against a plug 35 fixed in the end of such 55 socket, whereby it is normally pressed inward but may be pulled out by means of its head 36. In the side of the bracket 28 is a slot 37 adapted to admit the pin 32, and in the upper face of the bracket is a recess 38 60 adapted to admit a collar 39 on the locking pin, such recess and collar being wider than the slot. Thus when said collar occupies said recess the spindle is locked in upright position, but it may be readily unlocked and 65 swung aside by raising the locking pin head

and moving it outward. Although this is a convenient mode of securing the spindle and is preferred, other means of accomplishing the same result may be used within the scope for which I claim protection.

The distance between the brackets 26 and 70 28 limits the possible length of the filling thread bobbin, and the diameter of the head and the distance which must be preserved in a weave room between adjacent looms limit 75 the diameter of the bobbin. Preferably the frame member 25^b between the brackets is upright and parallel with the post frame, while between the upper bracket and its junction with the horizontal member 25^a it is 80 inclined for the double purpose of locating the bobbin as near as practicable to the post and thereby utilizing the space beneath the head, and of bringing the center of gravity of the entire bobbin underneath the shuttle base.

A spreader for opening the shed to permit passage of the shuttle and bobbin without interfering with the warp yarns is constructed of two pairs of bars 40, 41 and 42, 43, respectively, arranged adjacent to the upper and lower ends of the bobbin and supported by a rod or equivalent frame 44, 45, 46 which is secured to the forward edge or part of the rigid shuttle frame bar 25 near the bend and the lower end of the latter, respectively. That part of the spreader supporting frame which is designated 45 is an upright member substantially parallel to and in the path traveled by the center of the bobbin and the inner spreader bar of each pair is rigid to the frame, but the outer bars or members 40 and 42 are pivoted at their forward ends to the supporting frame in order that they may be swung aside to permit the displacement of the bobbin spindle as previously described. Braces 47 of any suitable character limit the closing in movement of these hinged spreader members. Other braces may be arranged between the rigid shuttle frame bar and the spreader frame if desired or necessary to make the spreader sufficiently rigid. Ample space is afforded for sufficient bracing without interfering with the bobbin or with the traverse 110 of the shuttle thread from the bobbin to the weaving point.

The shuttle thread 48 passes from the bobbin through an eye 49 in the adjacent part 25^b of the shuttle frame and thence around a 115 guide wheel 50 pivoted in a bracket which is attached to the upright member 45 of the spreader frame. Thence the thread passes through an eye 51 in the inclined part of the shuttle frame, and over guides 52, 53 which 120 guide it around the rim of the loom frame head. Finally it passes through an eye in a shoulder 54 at the inner end of the shuttle frame member 25^a, and through suitable 125 guideways 55 formed in a packer 56, to the 130

weaving point. The packer is mounted by a pivot 57 on the end of the member 25^a and is provided with an adjusting and take-up screw 58 threaded through a lug 59 and bearing against the shoulder 54. Otherwise it is constructed and functions substantially like packers previously used in this art.

The diameter of the tube being woven is controlled by the cooperation of said packers 56 and a gauge tube 60 through which the tube passes as soon as woven. The gauge tube is mounted in a manner permitting its adjustment and replacement by tubes of other sizes in a manner well known in this art and, therefore, not described in detail here. A take-up mechanism for the finished tubing is indicated in Figure 1, but not shown in detail because I may use any of the mechanisms for this purpose already familiar in the art.

The driving shaft 19 is tubular in order to permit passage through it of any construction, such as a hose lining or cable, about which a fabric casing is to be woven; and it is made with as large a bore as strength and available space within the hollow post will permit in order to admit passage of as large linings, cables, etc. as possible. It rotates in bearings of any suitable character, and is supported in any suitable way. In the arrangement here shown its supporting means consists of a thrust bearing 61 which may be a ball bearing and rests on the upper end of the post 10. A cam 62 secured to the shaft 19 for operating the heddle mechanism, presently to be described in detail, serves as a collar on the shaft which rests upon the thrust bearing. On the lower end of the shaft is a pulley 63 or equivalent means for receiving power from an outside source.

The heddle motion is located below the path of the shuttle, preferably at the base of the central post, in order to give room for a long shuttle mounting. The heddles 64, 65 are arms carried by shafts 66 and 67, respectively, arranged parallel to one another and tangent to a circle concentric with the loom frame. The entire heddle motion consists of a series of groups, each group consisting of the shafts and arms or fingers just described, and these groups are arranged about the central post, being provided in such number and each of such length as to conform as closely as practicable to a circular outline. Obviously as the shafts are straight, the greater the number of groups, the more closely will these groups conform to the circumference of a circle. I have found that eight groups give close enough approximation to the circular outline for practical purposes without involving too great a multiplication of driving connections.

Of the two shafts of each heddle group one is outside of the other and at a somewhat lower level, an arrangement which is con-

ducive to the best effects in opening and changing the shed. At their ends these shafts are supported rotatably in brackets 68, and to the inner shaft of the group is affixed a gear segment 69. Meshing with the segment is a reciprocating rack 70 carried by the lower end of a bar 71 which passes through a guideway in the head 11 and carries a stud or roll 72 which enters a groove 73 in the cam 62 previously described. The lower end of the bar, which carries the rack, is guided by an open chair 74 which is bolted to the outside of the post 10. Transmission means between the two shafts is provided of such a character as to cause opposite and substantially equal oscillation of the shafts at the same time. One character of means suitable for this purpose consists in an arm 75 on one of the shafts carrying a pin 76 which occupies a notch or slot 77 in an arm 78 on the other of the shafts. Intermeshing gear segments or other equivalent machine elements may be used, however, with like effect for the same purpose.

The warp yarns pass from a creel or other holder of any suitable sort under a drum 781 and through eyes in a bar 782 beneath the base to the several heddle arms. Other guiding means known to those skilled in the art to which this invention relates may also be used. The heddle arms have eyes through which the warp threads pass and from which they extend around the rim of the head 11. Grooves 79 are cut in the bounding lips and cross the bottom of the shuttle guideway in sufficient number and so arranged as to accommodate all of the warp threads with a substantially equal angular spacing about the center of the loom. With each change of the shed half of the warps lie in these grooves beneath the shuttles. The alternate warps pass over and outside of the shuttles. In order to reduce interference of the shuttle frames with the outer warps to the minimum, the frame bars 25 are made as narrow as possible in that dimension which causes displacement of the warp threads, and the necessary strength is provided by widening them in the direction in which they travel, and they are reduced in thickness to a thin edge from their rear toward their advancing sides.

In the operation of the loom the central shaft 19 is driven by the pulley 63 or equivalent means and in turn propels the shuttles in their circular path by means of the gear 20, pinions 21, shafts 22 and pinions 23. At the same time the cam 62 actuates the heddle motion to change and open the shed in advance of the shuttle. Each heddle group acts as a unit in changing and opening the shed and on each down travel of its operating rack the heddle fingers on the inner shaft are swung from an outwardly inclined position to a substantially upright position and the heddle fingers on the outer shaft are swung

from a position inclined toward the post to an outwardly inclined position, while on the up travels of the racks the reverse action takes place. Of course the cam groove 73 has a sufficient amount of offset axially to give the required movement to the rack, and the groove likewise has a large enough number of such offsets to impart one of these movements to each rack in advance of each shuttle. If there are two shuttles the rack is moved once upward and once downward with each revolution of the cam, while if there are four shuttles each rack is given two of these movements. This design, even though the outside diameter of the loom is small, provides room for a cam large enough to make a quick change of the shed between shuttles without making the inclines of the cam groove too steep for smooth and easy running.

A wide enough opening is given to the shed by the heddle fingers to admit the advancing end of the spreader frame, and having once entered the shed formed by any heddle group, the side spreader bars 40, 41, 42, 43 hold the warp threads away from the bobbin while the upper and outer bar 40, in combination with the supporting rod 44, clears the outer warps from the upper part of the shuttle frame 25^b. The upper frame member 25^a of the shuttle slips under the outer warps.

If necessary, in order to prevent displacement of these warps by the shuttle, I may provide a fixed outer ring having fingers or teeth arranged beside the correct normal positions of the warps, in accordance with a well known and frequently followed practice. A suitable location for such ring is indicated in dotted lines at 80 in Figure 2, the shuttle frame bar having a cross groove 81 across which the warps bridge and into which the fingers of the retaining ring may project.

One of the conspicuous advantages derived by reason of this invention is that a loom of relatively small outside dimensions can be set up to weave a very large number of ends in a warp, and thereby to make tubes of large diameter. Since any number of warps less than the maximum may be woven in the same loom, it follows that a wide range of sizes of tube may be made. Translating this advantage into terms of factory practice, a larger number of looms capable of weaving tubes of the maximum size may be installed in a given floor space than has previously been possible, and a greater variety of tubing may be obtained from the operation of the same looms, all of which conduces to economy of plant investment and operation. The prime cause of these results is that the construction and location of the heddle mechanism and the very narrow width of individual heddle elements or arms, enables this entire mechanism to be comprised within a space of which the area is much less than that required for an equal number of heddle elements of any other

known construction and operated by heretofore known means.

Another conspicuous advantage is that a larger amount of filling can be carried in one loading of the shuttles than has been possible heretofore. This is obviously due to the fact that the bobbin is carried below the head of the machine frame and close to the post, which gives room for a bobbin of large diameter, and to the fact that the long vertical space between the heddle motion and the frame head enables the length of the bobbin to be greater than heretofore.

The heddle elements may be made of sheet metal stampings and may, therefore, be made very thin, for ample room exists for them to be made as wide as is necessary to give strength. Hence a large number of these elements may be mounted upon a shaft of short length. They may be so mounted in many ways, with or without provision for adjustment about their supporting shafts. One possible construction consists in stringing the elements on a sleeve 82 and securing them thereto by keys, the sleeve being rotatable on the shaft and carrying one or more set screws 83 by which it may be secured. Another possible construction exists in so bending the strip of which the finger is formed that a short tongue 84 is provided parallel to the main body of the finger and united thereto by a web 85. The tongue and the adjacent part of the finger body, being perforated with aligned holes, may be slipped on the shaft, and a set-screw 86 passed through a threaded hole in the web 85 secures the finger. It is also possible to adjust both shafts and their associated heddle elements in unison by removing the chair 74 and slipping the rack 70 out of mesh with the gear segment 69, shifting the heddle elements into the desired position, and reengaging the teeth of the rack with other teeth of the segment.

It will be evident that various changes may be made in the construction and arrangement of the loom and the several parts thereof without departing from the spirit of the invention or from the scope in which I claim protection.

The title and description of the machine herein described as a circular loom are not intended to import a limitation to machines included within the most narrow definitions of looms or to exclude machines known in the art as "braiders" of the circular type. The new principles of this invention are applicable to machines which are variously operated for weaving or interlacing strands, whether in the form of a circular weave or a circular braid, and whether such machines are called "looms" or "braiders." Hence in this specification the term "circular loom" is to be interpreted so as to include also machines which interweave strands in the form commonly understood under the term "braided."

What I claim and desire to secure by Letters Patent is:

1. A machine for circularly interweaving strands having a frame comprising essentially a post and a head of larger diameter than the post, a shuttle mounted to travel in a closed circuit around the head, and a heddle motion disposed around the post at a less distance therefrom than the circumference 70 of the head, the shuttle having thread carrying means arranged between the plane of the head and the plane of the heddle motion.
2. A machine for circularly interweaving strands comprising a frame having a post and a head of greater width than the post, a shuttle mounted on said head to travel about the axis thereof in a closed orbit, said shuttle having a thread-guiding part extending over the head toward said axis and a thread carrying portion extending from the head beside the post, and a heddle mechanism surrounding the post at the opposite side of said thread carrying portion from the head.
3. A machine for circularly interweaving strands comprising a post, a shuttle carrying guide surrounding the axis of the post and being of greater diameter than the latter, a heddle mechanism also surrounding the axis of the post in a different plane from that of the 90 shuttle carrying guide, and a shuttle mounted to travel in said guide and having thread holding means disposed between the plane of the guide and the plane of the heddle mechanism, the shuttle having also means for conducting thread from said holding means across said guide toward a weaving point within the circuit of the guide.
4. A machine for circular interweaving strands comprising a post, a shuttle carrying guide surrounding the axis of the post and being of greater diameter than the latter, a heddle mechanism also surrounding the axis of the post in a different plane from that of the shuttle carrying guide, and a shuttle 100 mounted to travel in said guide and having thread holding means disposed between the plane of the guide and the plane of the heddle mechanism, said heddle mechanism and said thread holding means being nearer to the axis of the post than is the said guide.
5. In a machine for circularly interweaving strands, a post, a shuttle carrying guide surrounding the axis of the post, a shuttle mounted to travel in said guide and having a suspended thread carrying part located below the guide and nearer to the post than the outer circumference of said guide, and a heddle mechanism surrounding the post below the thread carrying part of the shuttle 110 and being nearer to the post than is said outer circumference.
6. A machine for circularly interweaving strands comprising a post, a shuttle guide surrounding the post and supported thereby, a driving shaft within the post, a cam on said 120 driving shaft, a heddle mechanism surrounding the post and consisting of a series of heddle units each comprising oscillative shafts and arms carried by said shafts, and a motion transmitting member extending from said cam and coupled with one of said shafts to impart oscillative movement thereto and a connection between the two shafts arranged to transmit oscillative movement in the opposite direction from one to the other.
7. A machine for circularly interweaving strands comprising a post, a shuttle guide supported by the upper end of said post and surrounding the axis thereof, a driving shaft contained within the post, a cam fixed to said shaft and overlapping the upper end of the post, a gear wheel fixed to the shaft above the cam, radially arranged transmission shafts mounted by the shuttle guide support, 130 pinions on said radial shafts arranged, respectively, to mesh with said driving gear and to mesh with teeth on a shuttle traveling in said guide, a shuttle comprising a base fitted slidably in the guide and having teeth to mesh with the last-named of the aforesaid pinions, an arm carried by the shuttle base extending around the guide and inclined downwardly toward the post, a bobbin carried by the lower part of said arm, a series of unit heddle mechanisms surrounding the post below the path of said bobbin, and motion transmitting connections passing from the cam to several unit heddle mechanisms.
8. A machine for circularly interweaving strands comprising means for guiding a shuttle in a closed orbit, a shuttle traveling along said guiding means and carrying a bobbin in a plane which is displaced in the axial direction from the plane of the guiding means and a heddle motion in still another plane further offset than, and in the same direction as, the bobbin from the plane of the guiding means.
9. In a machine for circularly interweaving strands, in combination with a shuttle guide, a shuttle comprising a base fitted to travel along said guide, an arm secured to said base and extending around the guide toward the axis of the guide, and a filling thread bobbin carried by said arm relatively near to said axis.
10. In a machine for circularly interweaving strands, a shuttle guide constructed to establish a closed path for the travel of a shuttle, and a heddle mechanism surrounding the axis about which the said guide extends and being nearer such axis than the outermost parts of the guide, said mechanism including heddle arms which are arranged to oscillate toward and away from said axis, said arms having eyes through which warp threads are adapted to pass to and around the outer circumference of the shuttle guide to the weaving point, and a shuttle constructed and arranged to travel in said guide and having a thread-carrying portion disposed between the 130

guide and the location of said heddle mechanism.

11. In a machine for circularly interweaving strands, a shuttle guide constructed to establish a closed path for the travel of a shuttle, and a heddle mechanism surrounding the axis about which the said guide extends and being nearer to such axis than the outermost parts of the guide, said mechanism including 10 heddle arms which are arranged to oscillate toward and away from said axis, said arms having eyes through which warp threads are adapted to pass to and around the outer circumference of the shuttle guide to the weaving point, said guide having substantially radial grooves in its shuttle engaging parts whereby to receive those warp threads over which the shuttle passes.

12. A heddle motion comprising a series of 20 unit mechanisms surrounding a central point, each unit comprising inner and outer shafts, connecting means between the shafts compelling them to oscillate oppositely to one another when either is oscillated, heddle arms secured to said shaft and driving means coupled to one of said shafts for imparting oscillative movement thereto.

13. In a machine for circularly interweaving strands, a frame, a driving shaft mounted 30 within said frame, a heddle driving cam carried by the shaft, a heddle motion consisting of a series of unit mechanisms surrounding said shaft, each unit consisting of two shafts and heddle arms secured to the shaft so arranged that by oscillation of said shafts said arms are moved from a position approximating parallelism with the driving shaft to a position substantially in a plane at right angles to the shaft, a connection between the inner shaft and said driving cam for imparting oscillative movement to said shaft, and transmission connections between the two shafts arranged to impart opposite oscillations at the same time to the outer shaft.

14. A machine for circularly interweaving strands as set forth in claim 13 in which the connection between the inner shaft of the unit heddle mechanism and the driving cam consists of a gear segment secured to said shaft, a rack movable endwise and running in mesh with said segment, and a stud connected with the rack and so engaged with the cam as to move the rack endwise when the cam is rotated.

15. A machine for circularly interweaving strands comprising a supporting structure having means for holding warp strands radiating from the weaving axis, a plurality of filling yarn carriers mounted to rotate about the weaving axis and located at one side of the location of said warp-holding means and relatively near the weaving point, separate strand guiding means associated with each of said carriers for guiding the filling strands therefrom to the plane of the warp-holding

means, and means for progressively changing the shed between the successive strand guiding means.

16. A machine for circularly interweaving strands, comprising shuttle operated 70 means for assisting in forming a circular shed, means additional to the shuttle operated means for forming and changing the shed, warp supporting means surrounding the weaving point constructed to support the 75 warp yarns radiating from the weaving point substantially in a plane perpendicular to the weaving axis, and a shuttle arranged to hold a supply of filling yarn at one side of the plane of said supporting means.

17. A machine for circularly interweaving strands, comprising means for supporting warp yarns substantially in a plane and radiating from the weaving point, shuttle operated means for assisting in forming a circular shed, means additional to the shuttle operated means for changing the shed, means for holding a supply of filling yarn outside of the said plane, and means for guiding the filling yarn from said supply into said plane. 85

18. A machine for circularly interweaving strands, comprising a substantially circular warp supporting structure, a shuttle mounted to rotate about the axis of said structure, and provided with means for carrying a supply of filling yarn at one side of the plane of said structure, and with means for guiding the filling yarn from the source of supply around the perimeter of said structure and into the weaving plane, means mounted upon the shuttle for assisting in forming a shed, and means in addition to the means upon the shuttle for forming the warp yarns into a shed and changing the shed.

19. In a machine for circularly interweaving strands, a warp guiding structure concentric with the weaving axis and extending outwardly in all directions radially of said axis, shed changing means in addition to the after-mentioned shuttle operated means, 105 and a shuttle including a bobbin mounted to rotate about said axis in a plane axially displaced from the weaving point and at one side of said radially extending structure and having operating means for assisting in forming a shed.

20. In a machine for circularly interweaving strands, a warp guiding structure concentric with the weaving axis and extending outwardly in all directions radially of said axis, a shuttle including a bobbin mounted to rotate about said axis and being axially displaced from the weaving point, said shuttle also having means to guide the filling yarn on its way to the weaving point outwardly beyond the limits of said warp-guiding structure and means to assist in forming a shed, and means in addition to the shuttle means for forming a shed in the warp.

21. A circular loom, comprising means in 130

addition to the after-named shuttle carried means for forming and changing a circular shed, a shuttle mounted to revolve about the axis of the said shed, and having shed forming means, and a bobbin mounted on the side of the shuttle and displaced in an axial direction from the plane of the shed, said shuttle having means for guiding the filling yarn outwardly from said axis and into the plane of the shed.

22. A circular loom comprising means for holding warp threads in radial arrangement around the weaving point and means additional to and cooperative with the after-named shuttle means for so moving said

threads as to form the shed, a shuttle having shed forming means rotatable about an axis substantially aligned with the weaving point, said shuttle having filling yarn-guiding means at a substantial distance from said axis, and a bobbin mounted on the shuttle at one side of the plane or planes in which said radially arranged threads lie, and with its center nearer to said axis than the part of said guiding means which projects far- 20
thest from the axis.

In testimony whereof I have affixed my signature.

HENRY E. BRYANT.
